UNITED STATES PATENT OFFICE.

EDWARD L. WILKISSON, OF BROOKLYN, NEW YORK.

DESIGN FOR AN AUTO RADIATOR-TANK WHISTLE.

Application filed February 6, 1922. Serial No. 576. Term of patent 7 years.

To all whom it may concern:

Be it known that I, EDWARD L. WILKISSON, a citizen of the United States, residing in the borough of Brooklyn, county of Kings, city and State of New York, have invented a new, original, and ornamental Design for Auto Radiator-Tank Whistles, of which the following is a specification, reference being had to the accompanying drawing, forming part thereof.

Fig. 1, is a top view of an auto-radiator tank whistle, showing my new design;
Fig. 2, is a bottom view thereof;
Fig. 3, is a side elevation thereof; and
Fig. 4, is a side elevation thereof, taken at right angles to Fig. 3.

I claim:

The ornamental design for an auto-radiator tank whistle, as shown.

EDWARD L. WILKISSON.
